Primary Examiner — Adir Aronovich*Assistant Examiner* — Roselynne Cody(74) *Attorney, Agent, or Firm* — Modiano & Associati; Albert Josif; Daniel O'Byrne(57) **CLAIM**

The ornamental design for a screwdriver handle, as shown.

DESCRIPTION

FIG. 1 is a perspective view of a screwdriver handle showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a further perspective view thereof;

FIG. 9 is a further perspective view thereof; and,

FIG. 10 is a further perspective view thereof.
